[57] CLAIM

The ornamental design for a framework member, as shown and described.

DESCRIPTION

FIG. 1 is a perspective view of the top, front and right of a framework member showing my new design;
FIG. 2 is a front elevational view of the framework member shown in FIG. 1;
FIG. 3 is a right side view of the framework member shown in FIG. 1;
FIG. 4 is a left side view of the framework member shown in FIG. 1;
FIG. 5 is a rear elevational view of the framework member shown in FIG. 1; and,
FIG. 6 is a top view of the framework member shown in FIG. 1, the bottom being a mirror image thereof.
